2 SHEETS—SHEET 2.

By this Attorney Abraham Slotoroff
Counsel Davis

UNITED STATES PATENT OFFICE.

ABRAHAM SLOTOFF, OF NEW YORK, N. Y., ASSIGNOR OF ONE-THIRD TO IRVING SAGER, OF BROOKLYN, NEW YORK, AND ONE-THIRD TO CHRISTIAN EBERSTALLER, OF ROSELLE, NEW JERSEY.

HEAD-GEAR.

1,262,111.

Specification of Letters Patent. Patented Apr. 9, 1918.

Application filed December 14, 1917. Serial No. 207,109.

To all whom it may concern:

Be it known that I, ABRAHAM SLOTOFF, a citizen of the United States, and a resident of the borough of Bronx, county of Bronx, 5 city and State of New York, have invented certain new and useful Improvements in Head-Gear, of which the following is a specification.

This invention relates to improvements in 10 headgear especially applicable for use by soldiers.

One important object of the invention is to provide a combined cloth campaign hat and steel helmet in which the crown of the 15 cloth hat is detachably held within the helmet, whereby the helmet may be removed when desired and the inner cloth hat alone worn.

Another important object of the invention 20 is to provide cushioning means interposed between the steel helmet and the head of the wearer adapted to relieve the head from direct pressure of the helmet and to absorb the shock of blows upon the helmet from the 25 impact of shell fragments, bullets, rifles, and the like.

A further important object of the invention 30 is to provide a hat adapted to be made of a standard size and adjustable to fit practically any size of head.

A further object of the invention is to provide a campaign hat adapted for use in both 35 mild and inclement weather, and which may be worn in connection with a steel helmet if desired.

In the drawings, Figure 1 is a perspective view of the cloth campaign hat, showing the ear and head protecting flap in its unfolded or depending position;

40 Fig. 2 a similar view, the protecting flap being folded within the crown of the hat;

Fig. 3 a top plan view of the cloth hat;

Fig. 4 a vertical longitudinal section showing the combined steel helmet and hat; and

45 Fig. 5 a front view of the combined hat and helmet, the steel helmet being shown in vertical section.

The convertible campaign hat and helmet lining is formed with a substantially circular crown portion having a top 1 of woven fabric, preferably khaki, and a body portion 50 2, preferably formed of the same material as the top 1. The top 1 is provided with a woolen or other lining 3, and the body por-

tion 2 is lined with a ply of cheese cloth or 55 canvas 4, and an inner ply of suitable relatively stiff fabric 5. The relatively stiff two-ply lining permits the body portion to be readily flexed but is sufficiently stiff to normally hold the body portion of the crown 60 upright, as shown. The lining 3 is held to the top 1 of the crown by two rows of stitches 6. A tape or annular strip 7 of khaki fabric is folded over the upper edge of the lining 4 and 5 and is held thereto by 65 a row of stitches 8. A row of stitches 9 passes through the tape 7, lining 4 and 5, top 1, and the lining 3. The lower edge of the tape 7 is stitched to the upper edge of the body 2 of the crown by a double row of 70 stitches 10 passing through the tape 7, body 2, intermediate lining 4 and inner lining 5. The lower edge of the body 2 of the crown is folded about the lower edges of the linings 4 and 5 and is secured by a row of stitches 75 11 which pass through both folds of body 2, lining 4, lining 5, the upper edge of a multiply vizor, and the lower or outer edge of an adjustable crown-lining 12.

The vizor is relatively stiff, but is preferably so constructed that it may be folded upwardly within the crown if desired. As shown, the vizor is formed of two plies 13 and 14 of woven fabric, such as khaki, between which is held a ply of stiffening fabric 15, such as canvas or the like, and the upper surface of the vizor is covered by a 80 ply of waterproof fabric 16, such as oiled silk. The several plies of material are held together at their upper ends by a row of 85 stitches 17 which pass therethrough and through the turned up outer or lower edge of the adjustable crown-lining 12. The several plies of the vizor are stitched together at their lower ends by a row of stitches 18. 90

A plurality of ventilating openings 19 are formed in the top 1 of the crown and the lining 3 thereof, and the edges of said openings are protected by eyelets 20. The crown of the hat is provided with a flap 21 95 which depends from the lower edge thereof and extends from a point at one side of the vizor around the rear of the hat to a point at the opposite side of the vizor. The flap 21 is preferably formed of two plies of woven fabric, as khaki, and is adapted to protect the back of the head and neck and also 100 the ears. When the weather is not cold or 105

inclement the flap may be folded within the crown, as indicated in Fig. 2. The upper edge of the flap 21 is held to the crown of the hat by the rows of stitches 11 and 17, and 5 the forward and lower edges of the two plies of material forming the flap are held together by a row of stitches 22. The flap 21 is provided at each side with a pair of apertures 23, the edges of which are protected 10 by eyelets 24. The openings 23 are so positioned as to be opposite the ears of the wearer when the flap is in use, and thus serve to permit the wearer to readily hear any sound, order, or the like, while the ears 15 are covered by the flap.

A plurality of compressible devices are interposed between the crown and the crown-lining 12 of the hat. These devices may be of any suitable construction and any 20 desired number thereof may be employed. As shown, each device comprises a loop or tube 25 of suitable fabric held by the rows of stitches 11 and 17, and a length of rubber tubing 26 held within the fabric loop or 25 tube. The compressible cushions thus formed not only serve to assist in yieldably supporting the weight of the combined campaign hat and steel helmet, but also adapt the hat for wear by persons having heads 30 of different sizes, as it will be obvious that said devices will compress or flatten to a greater or less degree when the hat is placed upon the head, the degree of compression being dependent upon the size of the head 35 of the wearer. To further adapt the hat to fit heads of different sizes, the crown lining 12 is provided with a large circular opening at the top or center thereof and is provided with a draw-string 27 extending around said 40 opening. It will be obvious that the crown lining 12 may be contracted or expanded at will by means of the draw-string 27 to cause the lining to fit heads of different sizes. By employing the compressible cushions and 45 adjustable lining above described it is possible to make hats of a uniform or standard size which may be readily adjusted to fit a head of any ordinary or normal size.

The fabric campaign hat above described 50 is adapted to be worn in connection with a steel helmet to form a trench hat, or hat adapted for wear on the battle-field, and avoids the necessity of providing a soldier with a steel helmet having a permanent 55 fabric lining or inner hat, and a separate fabric campaign hat, thus reducing the cost of equipment as well as the number and weight of the articles forming the field equipment carried by the soldier. The steel 60 helmet 28 is detachably held in place about the crown of the fabric hat by means of a separable fastener of the well-known snap or glove fastener type, the male member 29 of which is rigidly held to the inner side 65 of the helmet centrally of the crown portion

thereof, and the female member 30 of which is held to the top of the crown of the fabric hat.

The fabric campaign hat is provided with a throat strap 31 adapted to hold the hat securely upon the head, and also adapted to assist in holding the helmet 28 in place when the hat is worn in connection with the helmet. The free end of the strap 31 is adapted to be passed through a slide buckle or other 70 fastening device 32, of any suitable construction, held to the free end of a short strap 33. The straps 31 and 33 are held to the hat by the rows of stitches 11 and 17. When both the hat and helmet are worn, the 80 straps 31 and 33 are passed through the usual metallic hinged rectangular loops or eyes 34 pivotally held at 35 to the under side of the helmet 28 at opposite sides thereof.

A plurality of cushioning devices are secured to the exterior of the side portions of the crown of the fabric hat, and a plurality of similar cushioning devices are held to the top of the crown portion of the hat. Each of the cushioning devices comprises a loop 90 or tube of fabric 36 within which is held a length of rubber tubing 37. The fabric loops 36 at the sides of the crown are held by the rows of stitches 10, and the fabric loops on top of the crown are held by means 95 of rows of stitches 38 and tapes or strips 39 of suitable fabric. The tapes 7 and 39 and the stitches 10 and 38 serve to securely hold the fabric loops 36 in place. The cushioning devices formed by the fabric loops 36 and 100 rubber tubes 37 serve to yieldably hold the heavy steel helmet 28 in spaced relation with the head and serve as shock absorbing devices to relieve the head from the shock of the impact of bullets, shell fragments, and rifles, 105 etc.

From the foregoing it will be observed that a head-gear for soldiers has been provided which is adapted for use in both mild and inclement weather; which is readily 110 convertible from a winter hat into a summer hat; and which is readily convertible to adapt the same for wear as an ordinary fabric campaign hat or as a helmet suitable for wear on the battle-field. It will also be 115 seen that the hat is readily adjustable to fit heads of different sizes, and that means is provided for relieving the head of the direct pressure of the heavy and rigid steel helmet and for absorbing the shock of blows upon 120 the helmet.

What I claim is:—

1. A metallic helmet having an inner supplemental fabric crown detachably held within the same, a fabric lining held within 125 said supplemental crown, means for varying the size of the lining, and compressible means interposed between said lining and the supplemental crown adjacent the lower edges thereof.

2. A headgear comprising a crown portion having an expandible and contractible lining, means for holding the lining in its adjusted condition, and compressible means interposed between the crown and the lining adjacent the lower edges thereof.
3. A headgear comprising a crown portion having an expandible and contractible lining, means for holding the lining in its adjusted condition, compressible means interposed between the crown and the lining adjacent the lower edges thereof, and a protecting flap depending from the crown portion and adapted to cover the back and sides 15 of the head, said flap being adapted to be folded within the crown lining when not in use.
4. A convertible headgear comprising a fabric hat, a metallic helmet adapted to fit 20 over the hat, resilient projecting means held to the exterior of the crown portion of the fabric hat and loosely engaging the interior of the metallic helmet to yieldably hold the metallic helmet in spaced relation with the 25 fabric hat, and means for detachably holding the metallic helmet to the crown portion of the fabric hat.
5. A convertible headgear comprising a metallic helmet, a fabric hat adapted to fit 30 within the crown portion of the helmet, resilient cushioning means interposed between the hat and helmet, apertured projecting devices held to the inner surface of the helmet at opposite sides thereof, and a throat strap 35 held to the hat and adapted to pass through the apertures in said projecting devices to detachably hold the helmet about the hat.
6. A convertible headgear comprising a metallic helmet, a fabric hat adapted to fit 40 within the helmet, a plurality of loops of fabric held to the sides and top of the crown of the hat, a length of rubber tubing held in each of said loops, and means for detachably holding the hat and helmet together.
- 45 7. A convertible headgear comprising a metallic helmet, a fabric hat adapted to fit within the crown portion of the helmet, resilient cushioning devices held to the top and sides of the fabric hat and adapted to loosely 50 engage the interior of the metallic helmet, an expandible and contractible fabric lining held to the interior of the fabric hat along its lower edge, draw-string means for holding the lining in its adjusted position, compressible means interposed between the hat 55
- and lining adjacent the point of connection of the lining with the hat, apertured projecting devices held to the metallic helmet at opposite sides thereof, and a throat strap held to the fabric hat and adapted to pass 60 through the apertures in said projecting devices to detachably hold the helmet about the hat.
8. A convertible headgear comprising a metallic helmet, a fabric hat adapted to fit 65 within the helmet, a plurality of loops of fabric held to the top and sides of the crown of the hat exteriorly thereof, lengths of rubber tubing held in said loops, apertured projecting devices held to the helmet at 70 opposite sides thereof, and a throat strap held to the fabric hat and adapted to pass through said apertured projecting devices to hold the headgear upon the head.
9. A convertible headgear comprising a 75 metallic helmet, a fabric hat adapted to fit within the helmet, a plurality of loops of fabric held to the top and sides of the crown of the hat exteriorly thereof, lengths of rubber tubing held in said loops, apertured 80 projecting devices held to the helmet at opposite sides thereof, a throat strap held to the fabric hat and adapted to pass through said apertured projecting devices to hold the headgear upon the head, and a 85 separable fastening device for detachably holding the hat within the helmet embodying cooperating members held to the top of the hat and the interior of the crown of the helmet.
- 90 10. A convertible headgear comprising a metallic helmet, a fabric hat adapted to fit within the helmet, a plurality of loops of fabric held to the top and sides of the crown of the hat exteriorly thereof, lengths of 95 rubber tubing held in said loops, apertured projecting devices held to the helmet at opposite sides thereof, a throat strap held to the fabric hat and adapted to pass through said apertured projecting devices to 100 hold the headgear upon the head, and a flap held to the lower edge of the fabric hat adapted to cover the back and sides of the head and having apertures adapted to register with the ears of the wearer, said flap depending within the throat strap and being 105 foldable within the crown of the fabric hat.

This specification signed this twelfth day of December, A. D. 1917.

ABRAHAM SLOTOFF.
